United States Patent Office.

BENJAMIN NOTT, OF ALBANY, NEW YORK.

Letters Patent No. 98,096, dated December 21, 1869.

ILLUMINATING-STOVE

The Schedule referred to in these Letters Patent and making part of the same.

To all whom it may concern:

Be it known that I, BENJAMIN NOTT, of Albany, in the county of Albany, and in the State of New York, have invented a new and useful Improvement in Illuminating-Stoves; and I do hereby declare that the following is a full, clear, and exact description thereof, reference being had to the annexed drawings, making a part of this specification, in which—

Figure 1 represents a perspective view of stove embodying my improvements.

Figure 2, a vertical section through centre from back to front.

Figure 3, a central vertical section of base of stove at right angles to fig. 2.

Figure 4, a vertical section of fuel-feeder.

Figure 5, a vertical section of outside attachment for fuel-feeder.

Figure 6, top view of bench or rests for fuel-feeders.

Figure 7, plan of feeders and illuminators.

Figure 8, sectional view of feeders.

In all, the same letters refer to the same parts.

My invention relates to a parlor-stove, which serves a double purpose, namely, of heating and illuminating.

My improvements consist in the construction, combination, and arrangement of sundry parts belonging to and constituting the stove, as will more fully appear from the following description and claims.

To enable those skilled in the art to make and use my invention, I will now proceed to describe its construction and operation.

The outer casing of the stove, marked O in the drawings, may be made of a semicircular form, the straight front side of which is permanently closed by a suitable plate down to the door y.

The semicircular casing is considerably enlarged around the coal or fuel-chamber, so as to form a bench, N, on the outside around and above such coal-chamber.

This bench is provided with a number of apertures, around which annular flanges or collars, F, are formed, and through which the fuel is fed into the fuel-chamber.

The lower front side of the stove is closed by the door y, on which a chute or hopper, I, is formed, communicating with the fuel-chamber, so that fuel can be introduced into the stove from all sides.

A smaller door, M, gives access to the ash-pit.

A represents the ash-pit, formed by upright flanges running from the front to the rear of the stove, leaving a space upon each side, between them and the outer casing of the stove, as clearly shown in fig. 3.

Upon the top of the flanges forming the ash-pit, the grate e is placed.

B is the fire-pot or fuel-chamber, which rests upon the flanges forming the ash-pit. It is made sloping

outwardly from its base to its upper end, which is so constructed as to fit snugly in the casing.

The fire-pot is set loosely in the stove through the door y, through which it can be withdrawn when it becomes worn or burned out, and a new one inserted without disturbing any other part of the stove.

The fuel is received from the feeders upon the flaring flange of the fire-pot, from which it slides toward the centre of the same; the burning of the fuel being from the centre of the fire-pot to its circumference.

G represent movable fuel-feeders, of which there are to be as many as there are apertures in the bench N.

These feeders are cylinders, made of sheet-metal or other suitable material, fitting snugly over the collars F. Their upper ends are closed by caps, as shown, and they are to be provided with handles, by which to carry them.

In their lower ends a valve, k, is inserted, to regulate the amount of fuel to be fed into the fire-pot, as well as to form a bottom to them while they serve the purpose of hods; for these feeders are to be filled with fuel at the coal-bin, and are then carried back into the room, and placed over the apertures in the bench N of the stove. They may be made so that the lower end of one fits over or in the upper end of another.

This arrangement of portable fuel-feeders in connection with a stove will be appreciated by housekeepers on account of its cleanliness.

By thus employing several feeders, with valves to regulate the discharge of their contents, as many different kinds of fuel may be used, such as hard coal, soft coal, concreted combustibles, &c., and these various kinds of fuel can be fed into the stove in such relative proportions as to produce the best results.

C is a hot-air chamber around the ash-pit and the fire-pot, communicating with the external atmosphere by the holes w w in the base-plate of the stove, under which the pan x is suspended.

D is the combustion-chamber, the wall of which, formed by the outer casing of the stove, is provided with several windows, L L², &c., alternating with the fuel-feeders. Other windows, K K², &c., are arranged in the front plate of the stove, as shown in fig. 1. All these windows are constructed of glass, or other transparent substances.

The rear windows may be provided with reflectors, Q, so arranged as to throw the light into the room.

These windows are arranged at various points in the stove for the purpose of illuminating the room; and in order to obtain a brilliant light in the stove, at the same time aiding in the combustion, I introduce several pipes, g h, into the stove, at various points, through which hydrocarbon-oils, or other luminous inflammable liquids may be supplied to the fire.

E represents a dome or crown-sheet inserted in the stove above the combustion-chamber, reverberating, and thus intensifying the heat.

A damper, f, is arranged in the top of the dome, which can be opened or partially opened, as may be found necessary.

Above this dome, and in the upper part, or second story of the stove, another fire-pot, B², is located, surrounded by an outer casing, so as to form an air-space, e, around it, to which air for the support of combustion is supplied through the pipes d d. The intention is to burn hydrocarbon-oils, or other inflammable liquids in this fire-pot, but solid fuel may be burned therein in combination with liquid.

The liquid fuel is introduced into this fire-pot through the pipe a, provided with suitable valves or cocks, as shown in figs. 2 and 4, or through the pipe P, as shown in fig. 5.

R is the exit-pipe in the upper part of the stove, through which the gaseous products of combustion escape into the flue.

Having thus described my invention,

What I claim, then, as new, and desire to secure by Letters Patent, is—

1. A portable fuel-feeder for stoves, provided with a valve for regulating the supply of fuel, said valve to act as a bottom for the feeder when it is removed for filling.

2. A stove provided with a series of portable feeders, G, whereby various kinds of fuel may be supplied to the combustion-chamber, substantially as shown and described.

3. A stove provided with two or more fire-pots or

combustion-chambers, one above another, and separated from each other by means of a crown-sheet provided with a damper, substantially as shown and described.

4. The illuminators or windows K K² and L, made of glass, mica, or any transparent translucent substance, and placed at intervals in the back, and sides, and at the front of stove, substantially as shown and described.

5. The fire-pot or chamber B², above the crown-sheet E, surrounded by an air-space, e, to which air is supplied by means of the air-pipe d, substantially as and for the purposes described.

6. The door y, forming the lower front of the stove, constructed so as to allow of the removal of the fire-pot or furnace B, substantially as set forth.

7. The removable fire-pot or furnace B, substantially as described.

8. The air-chamber O, and pan z, for the circulation of the air, substantially as and for the purposes described.

9. The hydrocarbon-feeder a, for supplying fuel to the upper combustion-chamber B², substantially as shown and described.

10. A reflector, of tin or other suitable material, placed opposite a translucent surface of a stove, as described.

The above specification signed by me, this day of
, 18

BENJAMIN NOTT.
